TABLE ATTACHMENT

Gust J. Christenson, Chicago, Ill.

Application October 20, 1938, Serial No. 235,970

4 Claims. (Cl. 211—71)

This invention relates to improvements in table attachments and it consists of the matters hereinafter described and more particularly pointed out in the appended claims.

5 The improved attachment is especially useful in connection with card and other game tables, either of the folding or rigid type, or any other tables, to provide a support for one or more drinking glasses and a receptacle for receiving 10 the ashes from cigars, cigarettes and the like.

One of the objects of the invention is to provide a table attachment of this kind including 15 means for holding a drinking glass and for receiving cigar and cigarette and similar ashes and which means may be covered when not in use so as to be substantially flush with the top surface of the table top.

Another object of the invention is to provide 20 a table attachment which when operatively secured to one corner of the top of the table, serves two persons, with respect to the drinks and smokes used by said persons.

A further object of the invention is to provide 25 an attachment of this kind which is simple in construction for low cost production and which may be readily applied to a table top.

The above mentioned objects of the invention, as well as others, together with the advantages 30 thereof will more fully appear as I proceed with my specification.

In the drawings:

Fig. 1 is a perspective view of a table attachment embodying the preferred form of the invention, when in position at one corner of a table 35 top and in its open position ready for use.

Fig. 2 is a view similar to Fig. 1 showing the attachment in its closed position of non-use.

Fig. 3 is a top plan view of the attachment in its open position ready for use.

40 Fig. 4 is a longitudinal vertical sectional view through the attachment when in its open position for use, the plane of the section being indicated by the line 4—4 on Fig. 3.

Fig. 5 is a view similar to Fig. 4 showing the 45 attachment in its closed condition for non-use.

Fig. 6 is a transverse vertical detail sectional view through the attachment, on an enlarged scale, as taken on the line 6—6 of Fig. 3.

Fig. 7 is a vertical detail sectional view also 50 on an enlarged scale as taken on the line 7—7 of Fig. 3.

Referring now in detail to that embodiment of 55 the invention illustrated in the drawings, the improved attachment includes a plate-like sup-

porting member 10 and a plate-like cover mem- 5
ber 11. The member 11 is so operatively connected to the member 10 as to be moved from a position overlapping and substantially covering said member 10 to a position completely exposing the same. Preferably the member 11 is hinged at one end to one end of the member 10 as indicated at 12 for the movement above mentioned. The member 11 is stiffened by means of one or more longitudinal ribs 11a formed from integral parts of said member. 10

The member 10 is preferably made of sheet material and is of a somewhat elongated shape and is semicircular at that end opposite the hinged connection 12. In the semicircular end of the member 10 is a depression or recess 13 15 adapted to hold a drinking glass 14 as appears in dotted lines in Fig. 1. A circular opening is formed in the member 10 at a point between said hinged connection 12 and recess 13 respectively and this opening is defined by an inwardly and downwardly tapering flange 15 that best appears in Fig. 6. Said opening removably receives an ash receiving receptacle 16 that has an upwardly and outwardly flaring flange 17 for a seating supporting engagement upon the bottom marginal portion of the flange 15. 20
25

The receptacle is provided with a cross bar 18 which may be readily grasped by the fingers for removing the receptacle from the flange 15 for emptying and replacement. This bar also 30 forms a convenient part against which the ashes on a cigar or cigarette may be engaged for removal.

To provide a convenient rest for cigars or cigarettes, the member 10 is provided on opposite 35 sides, with transversely extending grooves 19—19 that are inclined downwardly to open through the flange 15 at a point slightly above the top edge of the flange 17 of the ash receptacle 16. Along the opposite sides and extending about the rounded end of the plate member 10 is a 40 raised flange 20, which not only stiffens the member 10 as a whole but which also provides a convenient portion whereby the attachment as a whole may be operatively secured in position 45 to a table top 21.

The member 11 is of an area and shape to fit 50 within the raised marginal flange 20. That end of the member 11 opposite the hinged connection 12 is semicircular as shown and is formed on that surface forming the top surface, when said plate is in its open position, with an upstanding annular flange 22 constituting a receiving portion for a drinking glass 23 as appears in dotted lines in Fig. 1. The center of the flange 22 is spaced 55

substantially the same distance away from the hinged connection 12, as the center of the recess 13.

When the member 11 has been swung about the hinged connection 12 into the closed position as shown in Figs. 2 and 5, wherein it overlaps the supporting member 10, and covers the recess 13 and opening as defined by the flange 15, its edges fit snugly within the inner edges of the flange 20 and the flange 22 is disposed within the recess 13. At this time, the exposed surface of the member 11 is flush with the top surface of the flange 20.

To releasably hold the plate member in this position, a portion 24 of the flange 22 may be bulged slightly to spring into a recess 25 formed in the upright wall of the recess 13 toward the semicircular end of the plate member 10 as best appears in Fig. 5. It is pointed out at this time that a portion of the rounded end of the plate member 11 is formed with a raised lip 26 under which the fingernail may be inserted to assist in opening the member 11 against the restraining action of the parts 24 and 25 before mentioned.

In applying the attachment to a table top, an opening 27 is formed in one corner thereof with its major axis disposed in a plane extending toward the diagonally opposite corner. Said opening, which best appears in Fig. 3, is of a shape to receive that part of the plate member 10 within the flange 20. Thus this flange rests upon the table top about the sides and the semicircular end of the opening 27. Devices such as small screws or bolts 28 may be employed to secure the flange to the table top.

As each attachment readily serves two persons, only two of such attachments are required for each table, located at diagonally opposite corners thereof.

When the member 11 is in its closed position, wherein it overlaps the member 10 as before described, it is substantially flush with the top surface of the table top. When said plate member is in this position, the table may be stored in the usual manner.

When said member 11 is in its opened position for use as appears in Figs. 1 and 3, the member 11 engages by means of its ribs 11a substantially flat upon and overhangs that corner of the table top, outwardly of the hinged connection 12. The attachment occupies but a small amount of space in its associated corner of the table top and forms a handy adjunct therefor.

While in describing the invention, I have referred in detail to the form, arrangement and construction of the attachment, the same is to be considered only in the illustrative sense so that I do not wish to be limited thereto except as may be specifically set forth in the appended claims.

I claim as my invention:

1. A table attachment of the kind described embodying therein a plate-like supporting mem-

ber adapted to be operatively secured to a table top, means providing a drinking glass recess at one end of said member, a second plate-like member having a hinged connection with the other end of said member, said second plate-like member being capable of a swinging movement from a position closing said recess to a position exposing said recess for use, and means on said second plate-like member for holding a second drinking glass and so arranged thereon that when said second plate-like member is in a position closing said first mentioned recess, said glass holding means on said plate-like member is disposed within said recess.

2. A table attachment of the kind described embodying therein a plate-like supporting member adapted to be operatively secured to a table top, means providing a drinking glass recess at one end of said member, a second plate-like member having a hinged connection with the other end of said member, means carried by said supporting member providing an ash receiving receptacle, said second plate-like member being capable of a swinging movement from a position closing said recess and ash receptacle to a position exposing the same for use, and glass holding means carried by said second plate-like member and so arranged thereon that when said second plate-like member is in the position closing said recess and said receptacle, said glass holding means is disposed in said recess.

3. A table attachment of the kind described, embodying therein a supporting member adapted to be operatively secured to a table top within the margin thereof, means providing a drinking glass holder in said member, a second member, means operatively connecting said two members together whereby they may be relatively swung about an axis in a plane perpendicular to the axis of said drinking glass holder from an open to a closed position and vice versa, and means providing a flange-like drinking glass holder in said second member adapted to be disposed in said first mentioned drinking glass holder when said two members are in a closed position.

4. A table attachment of the kind described, embodying therein a supporting member adapted to be operatively secured to a table top within the margin thereof, means providing a drinking glass holder in said member, means providing an ash receiving receptacle in said member, a second member, means operatively connecting said two members together whereby they may be relatively swung about an axis in a plane perpendicular to the axis of said drinking glass holder from an open to a closed position and vice versa, and means providing a flange-like drinking glass holder in said second member adapted to be disposed in said first mentioned drinking glass holder when said two members are in a closed position.

GUST J. CHRISTENSON.
